Primary Examiner — Wendy L Arminio*(74) Attorney, Agent, or Firm* — Cynthia Flanigan; Wayne Harper(57) **CLAIM**

The ornamental design for a sport bottle lid with straw and handle, as shown and described.

DESCRIPTION

FIG. 1 is a perspective view of a sport bottle lid with straw and handle showing my new design;

FIG. 2 is a front view thereof;

FIG. 3 is a back view thereof;

FIG. 4 is a left side view thereof. The right side being a mirror image of the left side;

FIG. 5 is a top view thereof;

FIG. 6 is a bottom view thereof;

FIG. 7 is another perspective view of the sport bottle lid with straw and handle of FIG. 1 shown with the straw feature in an open position and the handle feature in an alternative configuration; and,

FIG. 8 is a left side view thereof but with the straw feature shown in a closed position.

The broken lines depict portions of the sport bottle lid with straw and handle that form no part of the claimed design.
